United States Patent Office.

PETER SEE BALD, OF NEW YORK, N. Y.

Letters Patent No. 79,151, dated June 23, 1868.

IMPROVED COMPOUND FOR DESTROYING BED-BUGS AND OTHER VERMIN.

The Schedule referred to in these Letters Patent and making part of the same.

TO ALL WHOM IT MAY CONCERN:

Be it known that I, PETER SEE BALD, of the city, county, and State of New York, have invented and produced a certain new and useful Mode and Compound for Preventing and Destroying the Infestation of Bed-Bugs in Houses, Dwellings, and Rooms; and I do hereby declare that the following is a full, clear, and exact description of the same.

The object of this invention is to have a preventive of bed-bugs infesting walls, rooms, and houses, which can be used with whitewashing the walls of the same, and which is of small expense, and serves for long time with good effect.

To enable others skilled in the art to make and use my invention, I will proceed to describe its construction, and mode of using the same.

In order to prepare my compound, I take a vessel or pot, and put in three (3) parts of water, and mix therewith one-sixteenth ($\frac{1}{16}$) part of potash, and heat and boil the same. I then mix therewith one (1) part of lime, and also one-sixteenth ($\frac{1}{16}$) part of lard, and I heat the latter in a vessel which contains a portion of fluid mercury, so that the vapors of the mercury impregnate the lard. This compound is now well stirred and agitated, and mixed while it is warm. The compound is now complete and ready for use, and is laid on the wall, ceiling, &c., in the same manner as the ordinary whitewash.

From the foregoing, it is clearly seen that this compound is of a small expense additional to the ordinary whitewash, and can be prepared and used by no more competent persons than the persons now engaged or able to perform the ordinary whitewashing of walls; that the ingredients used therein are of no more injurious effect to those who live in rooms whitewashed with the above compound than with the ordinary compound of the whitewash now in use, and that if the compound is used from the beginning, when the house or walls are first whitewashed, the bed-bugs are prevented from infesting the said walls at all, without any or little extra labor, and little extra cost.

Having fully described my invention, what I claim therein, and desire to secure by Letters Patent, is—

1. In preventive for bed-bugs, a compound, which is used as a whitewash for walls, substantially as and for the purpose herein set forth.
2. The compound, composed of the ingredients herein described, or substantially the same, and for the purpose herein shown.

PETER SEE BALD.
